UNITED STATES PATENT OFFICE.

MURDOCH McGREGOR, OF BELLEFOURCHE, SOUTH DAKOTA.

FENCE-POST

1,053,522.

Specification of Letters Patent.

Patented Feb. 18, 1913.

Application filed March 1, 1912. Serial No. 680,967.

To all whom it may concern:

Be it known that I, MURDOCH McGREGOR, a citizen of the United States, and a resident of Bellefourche, in the county of Butte and 5 State of South Dakota, have invented certain new and useful Improvements in Fence-Posts, of which the following is a specification, reference being had to the accompanying drawings.

10 This invention relates to certain novel improvements in fence posts.

The primary object of my invention is to provide a composite fence post arranged to removably hold a wooden staple-receiving 15 core.

Another object is to provide a composite fence post with a middle, lengthwise running aperture, ending in a key slot, said aperture to receive a board which is fixed by 20 means of a wedge driven into the key slot.

With these and other objects in view, the present invention consists in the combination and arrangement of parts as will be hereinafter more fully described and particularly pointed out in the appended claim, it being understood that changes in the specific structure shown and described, may be made within the scope of the claim, without departing from the spirit of the invention.

25 In the accompanying drawings forming a part of this specification, and in which like numerals of reference indicate similar parts in the several views:—Figure 1, shows an elevational view of a fence post constructed according to my invention. Fig. 2, shows a lengthwise sectional view of the post. Fig. 3, shows a detail of the wire netting reinforcement. Fig. 4, shows a transverse sectional view of the fence post, showing the fence fabric as secured to the core. Fig. 5, shows an end view of the wedge.

In the raising of swine, poultry and certain other stock where the animals are kept in runs, it is found necessary to remove the 45 animals for certain periods to allow the vegetation to get a fresh start. Further, it is often desirable to plow the runs in order to turn the soil.

50 In my present invention, I provide a fence post which is non-rotting, being made of reinforced concrete, having a centrally positioned slot into which is fitted and secured a wooden board, to which the fence fabric is stapled or otherwise secured. This board 55 forms a core which is firmly secured by means of a wedge.

In the use of my fence, when it is desired to change the animals from one run to another, it is simply necessary to knock out the securing wedges, remove the cores, make a row of the fence fabric and connected cores, and insert the cores into another set of fence posts. From this, it will be understood that one fence fabric may be used with two sets of fence posts, so that while one plot is in use, the other has an opportunity to 60 revive. All that is necessary is to set the fence posts equidistant apart in every instance. This method further permits the fence fabric being reversed if it is found 65 that the lower edge shows signs of rusting.

70 In the accompanying drawings, the numeral, 1, indicates a fence post of conventional conformation and of suitable length, made of concrete, having the middle, lengthwise running slot, 2, which above ends in the bevel-edged key-way, 3. In order to strengthen the post, I embed therein a wire netting reinforcement, 5, the top, 6, of which is arranged to lie close to the upper surface 75 of the key-way, 3, as shown in Fig. 2.

Arranged to be placed into the slot, 2, is a board, 7, which forms a core, it being desirable that this board is of a thickness less than the width of the slot, 2, so that should 80 the board swell, no injury will be done to the post. Arranged to be driven into the key slot, 3, is a preferably triangular wedge, 8, by means of which the core, 7, is firmly held within the fence post; the fence fabric, 9, 85 is then stapled to the core, 7, as shown in Fig. 4.

90 From the foregoing, it will be noticed that the entire fence fabric with the connected cores, 7, can be instantly removed 95 from the posts, 1, in simply knocking out the wedges, 8. These wedges, 8, may be made of any suitable material.

The attachment of the fence fabric to the cores, it is, of course, understood, is effected 100 in any suitable workmanlike manner.

A fence post constructed according to my invention is simple and inexpensive in construction and both durable and efficient, and the adjustment of the core within the posts 105 can be made with ease, accuracy and despatch.

Having thus described my said invention, what I claim as new and desire to secure by United States Letters Patent, is:—

110 In combination with a fence post having a longitudinal aperture therein extending

from side to side, the upper end of said aperture forming a V shaped passage, a core removably received within said aperture and adapted to support fencing fabric, 5 and a triangular wedge adapted to be received within the V shaped passage to secure the core within said aperture.

In testimony whereof I affix my signature in presence of two witnesses.

MURDOCH McGREGOR.
